UNITED STATES PATENT OFFICE.

FRANK A. EPPS, OF NEW YORK, N. Y., ASSIGNOR TO FOAMITE-CHILDS CORPORATION, OF NEW YORK, N. Y., A CORPORATION OF DELAWARE.

METHOD AND APPARATUS FOR EXTINGUISHING FIRES.

Application filed February 7, 1921, Serial No. 442,987. Renewed June 6, 1925.

My invention relates to a method of and apparatus for producing and discharging fire extinguishing foam in which gas chemically developed by contact of foam-making solutions is utilized to place said solutions under discharging pressure, and it may be regarded in one aspect as an improvement or development of the patent to Erwin and Flory, No. 1,331,466, granted February 17, 1920, Reissue No. 15,355, May 16, 1922, in which mutually reactive solutions (respectively acid and basic) are normally kept separated in different containers from which they may be permitted to pass by gravity into contact in a mixing chamber from which gas under pressure thus generated therein is delivered to the respective solution containers, the solutions in which are thereby placed under discharging pressure and conveyed through solution delivery lines from the respective containers to a mixing device and discharge device. From this point of view my improvement consists in using extraneous force other than gravity, though by this language I do not mean to exclude gravity as one of the forces which may play a part in the operation, to bring the mutually reactive solutions into contact for producing the discharging pressure, the solutions being brought into contact by taking a portion of one of the solutions from its container and forcing it into contact with the other solution, or by taking portions of both solutions from their containers and forcing them into contact in a mixing chamber, the resulting gas in either case furnishing discharging pressure for both solutions. Compactness is secured by the avoidance of considerable, or if desired, of any head between the solution tanks and mixing chamber, such as is necessary with an exclusively gravity feed in order to drive the solutions through the solution lines which may be long and to deliver them to the mixing device at a relatively high pressure to insure a long range of foam stream. While increase in discharging pressure as compared with increase in head has been found to be disproportionately great, a few feet increase in head giving a pressure increase of from twenty to eighty pounds and an extension of foam range of from ten to forty feet, ability to get still better results without any head at all, or with but a slight head, is a marked advantage, particularly in apparatus required to

be readily portable. It has been found that the function of the moderate solution head may be supplied by a low power pump. More positive action is also insured with exact control and sureness of operation attained through avoidance of valves likely to corrode especially in the acid solution pipes.

It is characteristic of my invention that the rate of delivery of solution by the pump or pumps may be definitely controlled and varied by altering the pump speed and that the delivery ratio for the respective solutions may be fixed in advance, in accordance with the nature of the particular solutions employed, at unity or otherwise. It is thus true that the apparatus may be arranged in accordance with the generally prevailing foreseen conditions, yet with capability of manual variation in operation in accordance with pressure gauge and other current indications, so as to meet varying conditions, arising from time to time, as to length of delivery lines, foam stream, nozzle pressure required, etc. My invention may be otherwise embodied than in the apparatus illustrated. Additional advantages will more fully appear in the following specification.

Referring to the drawings:

Figure 1 is an elevation of the apparatus mounted on a wheeled truck, with parts in section and parts broken away;

Figure 2 is a vertical section of a modification also mounted on a wheeled truck;

Figure 3 is an elevation showing the application of my invention to chemical fire department motor driven trucks and illustrating the manner in which the present chemical tanks, usually carried as part of the tank equipment, may be converted into a foam generating system embodying my invention.

Figure 4 is an elevation of another modification embodied in a two-solution foam generating sprinkler installation employing a valveless dry pipe system in a plant in which economy of space is essential, automatic control from a point adjacent the fire being indicated; and

Figure 5 is a vertical longitudinal section of another modification in which the auxiliary mixing takes place in one of the solution tanks.

Referring to Figure 1, the main tank 5 is subdivided by partition 6 into tanks 7 116

and 8, containing respectively the A or acid, and the B or basic solutions, whose composition may be as disclosed in the patent to Walker, No. 1,186,248, dated June 6, 1916. The tank 5 is preferably mounted on the wheeled truck 9, 10 representing a tool box and 11 the hose box. Each solution tank has a charging inlet 12 and a discharge or flushing outlet 13. Solution delivery lines 14, 15 connected respectively at one end to pipe sections 16, 17, which extend into and terminate adjacent the bottoms of tanks 7 and 8 respectively, are reeled in the form of a twin hose line 18, the delivery ends of which are connected to a Siamese mixer 19, the mixing of the solutions and foam taking place in section 20, terminating in the nozzle 21, control valves 22 and 23 being preferably provided in the solution lines in the Siamese delivery system.

Operating pressure on the solution levels in the chambers 7 and 8 is supplied in the form of my apparatus as follows: I provide an auxiliary mixing chamber 24 connected to the tank 7 by pipes 25, 27, and to the tank 8 by pipes 26, 28, pipes 27 and 28 respectively, entering the respective tanks 7 and 8 and terminating adjacent the bottoms thereof in preferably bell mouth solution inlets 29 and 30. The mixing chamber 24 is connected by foam pipe 31 to piping 32, 33, 34, 35 which places the tanks 7 and 8 in permanent communication. The solutions in the tanks may be conducted at will through the pipes 25 and 26 and into the mixing chamber 24 for contact therein to generate a pressure foam, which rising through the foam pipe 31, as indicated by the arrows, is led back through piping 32, 33, 34, 35 to both the tanks, entering them preferably at the top, as also indicated by the arrows. The foam thus generated and led into the solution tanks performs in time of fire, the double function of equalizing the back pressure exerted in the communicating lines 25 and 26 by the foam in the mixing chamber 24, this equalization taking place by the pressure transmitted to the bell mouth inlets 29 and 30, and providing a discharging pressure to drive the solutions in the solution tanks through the solution lines 14 and 15 and the twin hose section 18 to the delivery and mixing station located remote from the generating system.

For compactness, certainty and ease of control, and for readily producing high discharging pressure in the tanks, I provide forcing means bringing into play extraneous force other than gravity, although gravity may also be a factor in the operation of effecting contact of the solutions. Such means are preferably located in the communications between the solution tanks and the mixing chamber 24, and take the form, in my present invention, of low power pumps 36 and 37, one for each solution, located respectively in the communicating means between each solution tank and the mixing chamber, these pumps being geared together for simultaneous action, by means of sprocket wheels 38 and sprocket chain 39, a crank handle 40 being connected to one of the sprockets for manual operation of the pumps. By turning the handle 40 portions of the acid and basic solutions will be forced from the solution tank into the mixing chamber 24, the pumps providing just sufficient pressure to forcibly eject the solutions under moderate pressure from the communicating pipes 25 and 26 into the mixing chamber 24, where they are compelled to come into intimate contact thereby producing the pressure foam. The operator, in turning the handle 40, may be guided by the pressure gauge 41 in determining the speed of rotation of the handle 40 necessary to provide the desired discharging pressure. It has been found that with this type of system a very small pressure supplied by the pumps 36 and 37 sufficient to provide forcible intermixture of the solutions in the mixing chamber 24 will result in the obtaining of a foam which will exert a relatively high discharging pressure on the solutions in the tanks 7 and 8, owing to the expansion of the solutions into foam, the expansion being eight volumes at atmospheric pressure.

The solution tanks, the mixing chamber, the conducting means and the pumps may, furthermore, be so arranged and located as to eliminate valves from the system, such arrangement securing a dry piping system and by the elimination of valves rendering the operation very reliable. To this end the communicating means 25 and 26 and the pipe sections 27 and 28 are so arranged as to provide a siphoning arrangement, as disclosed clearly in Figure 1 of the drawings, operation of the pumps causing the siphoning of the solutions in the solution tanks into the communicating lines 25 and 26 for conduction into the mixing chamber 24.

Referring to Figure 2, the tank 5' is also shown mounted on a wheeled truck 9', this tank being subdivided by a partition 6' into solution tanks 7' and 8' of unequal capacity preferably in the ratio of three to one, for the purpose of utilization of acid and basic solutions of different compositions requiring use in different proportions. The auxiliary mixing chamber 24' is here shown as located above the tank 5' instead of below the said tank, the communicating pipes 25' and 26' connecting the mixing chamber 24' with the solution chambers, pumps 36' and 37' being arranged in the line of communication, similar to that shown in Figure 1. The gearing 38', however, is so arranged as to provide a three to one ratio in order to feed one part of the A solution from chamber

7' to three parts of the B solution from chamber 8' into the mixing chamber 24'. The solution lines 14' and 15' and the twin hose section 18' and Siamese delivery system 19' are otherwise similar to the form shown in Figure 1 of the drawings.

Referring to Figure 3, my invention contemplates the conversion of the present type of fire department, soda and acid tank system, usually mounted upon combination chemical motor driven trucks, into a foam generating system. The two tanks 42 and 43 are located as shown in the drawings in the space between the seat 44 and the hose box 45, solution lines 46 and 47 being connected to the tanks and to the twin hose line 48, which, in turn, is connected to the Siamese delivery system 49. The means for generating the foam pressure comprises a mixing chamber 50 communicating with the solution tanks by means of the pipe sections 51 and 52, pumps 53 and 54 being located in the lines of communication 51 and 52 and being geared in equal ratio to feed equal quantities of the solutions in the tanks to the auxiliary mixing chamber 50, the pumps being controlled by crank handle 55, foam generated in the mixing chamber being led to the pipe sections 56 and 57 back to the solution tanks 42 and 43 for exerting the necessary operating pressure on the solutions therein.

Referring to Figure 4, the tank 58 is stationary, the arrangement being otherwise, and save for the delivery system, similar to that of Figure 3. The apparatus comprises a mixing chamber 50' located above the tank 58 and having the pumps 53' and 54' connected in the lines 51' and 52', which form the communicating means between the mixer 50' and the solution chambers in the tank 58, the foam pipe sections 56' and 57' being here also provided and connecting the mixer 50' with the top of the solution tank. The delivery system shown in Figure 4 is of the sprinkler type, having solution lines 60 and 61 connecting the sprinkler 59 or a series of such sprinklers to the solution chambers in the tank 58. This form of my invention also contemplates the motor operation of the pumps 53' and 54' and the automatic control of such motor operation, a motor 62, which may be mounted on the tank 58, being operatively connected to the pumps as shown, the leads from said motor being connected to power lines 63 and 64, through the interposed switch 65, 66. This switch is controlled by a solenoid 67 whose circuit is dominated by thermostats (not shown). In the event of fire the thermostat affected will close the circuit. The solenoid will attract its armature 65 against the contact 66, thus completing the power circuit to the motor for the simultaneous actuation of the pumps 53' and 54'.

Referring to Figure 5, the stationary tank 68 is divided by partition 71 into A (acid) chamber 69 and B (basic) chamber 70, from which lead respectively solution lines 72, 73, having portions 74 and 75 entering the respective chambers and terminating adjacent the bottoms thereof; it being understood that the lines 72, 73 may be connected to any type of solution mixing and foam delivery system, such, for example, as shown in the other figures. Instead of employing an auxiliary mixing chamber distinct from the solution chambers, as in the other figures, the mixing of the solutions may be made to take place in one of the solution chambers, preferably the basic chamber 70. In such a modification also a pump is employed to drive one of the solutions from one of the chambers into the other for mixture therein with the other solution. The pump 76, which may be hand or power, but is shown as having a hand crank 77, is in communication by pipe sections 78 and 79 with the acid chamber 69 and by pipe sections 80, 81 and 82 with the basic chamber 70, pipe section 82 being preferably provided with a plurality of feed apertures to insure rapid and widely extended contact and mixture of the solutions on operation of the pump. The pump 76 is preferably located below the level of the solution in the acid chamber 69 so that normally both the pump and part of the pipe section 80 are filled with acid solution and necessity of priming the pump thus avoided. In this form of the device also a pressure equalizing pipe 83 connects the solution chambers 69 and 70, this equalizing system being provided for conducting the pressure foam generated in the chamber 70 to the acid chamber 69. The pressure foam in the acid chamber 69 also performs the dual function of equalizing the back pressure exerted on the pump 76 and of producing operating pressure on the acid solution in the chamber 69 to drive the said solution through the solution line 72. Likewise the foam pressure in the chamber 70 functions to drive the basic solution in the said chamber through the solution lines 73 for mixture at a remote mixing chamber with the solution in the solution lines 72 for the production of the fire extinguishing foam ejected from a delivery system.

The foregoing description of various embodiments of the invention, while these are of course by no means exhaustive, has brought out special novel advantages inherent in it and has made clear the operation so that recapitulation is thought unnecessary.

Claims:

1. The method of producing and discharging a fire extinguishing foam which consists in discharging foam-making solutions from the containers thereof by taking a portion of the solution from one of said con-

1. Containers and forcing the same into contact with the solution of the other container by extraneous force other than gravity, thereby chemically developing a relatively high pressure gas, and utilizing such gas on the liquid surfaces in both said containers to produce discharge of said solutions, conducting said discharged solutions to a mixing device and discharge device.
2. The method of producing and discharging a fire extinguishing foam which consists in discharging foam-making solutions from the containers thereof by taking portions of the solutions from both of said containers and forcing the same into contact with each other in a mixing chamber by extraneous force other than gravity thereby chemically developing a relatively high pressure gas, and utilizing such gas on the liquid surfaces in both said containers to produce discharge of said solutions, conducting said discharged solutions to a mixing device and discharge device.
3. The method of producing and discharging a fire extinguishing foam which consists in discharging foam-making solutions from the containers thereof by pumping portions of one solution from its container into contact with the solution of the other container thereby chemically developing a relatively high pressure gas, and utilizing such gas on the liquid surfaces in both said containers to produce discharge of said solutions, conducting said discharged solutions by separate solution delivery lines from the respective containers to a mixing device and discharge device.
4. The method of producing and discharging a fire extinguishing foam which consists in discharging foam-making solutions from the containers thereof by pumping portions of both solutions from their respective containers into contact with each other in a mixing chamber, thereby chemically developing a relatively high pressure gas, and utilizing such gas on the liquid surfaces in both said containers to produce discharge of said solution, conducting said discharged solutions by separate solution delivery lines from the respective containers to a mixing device and discharge device.
5. The method of placing mutually reactive foam-making solutions under discharging pressure which consists in pumping foam-making solutions from the respective containers thereof in a predetermined ratio and forcing them into contact in a mixing chamber, thereby chemically developing a relatively high pressure gas, and conducting the same to the said containers to place the solutions therein under discharging pressure.
6. Fire extinguishing apparatus comprising separate containers for mutually reactive foam-making solutions, means for producing contact of the solutions by the use of extraneous force other than gravity to produce discharging pressure, means for conveying high pressure gas thus generated to the solution containers, and solution delivery lines communicating with said containers and with each other at a point remote therefrom.
7. Fire extinguishing apparatus comprising containers in which mutually reactive foam-making solutions are normally kept separate, a pump in communication with one of said containers for forcing solution from that container into contact with solution of the other container to produce high pressure gas, conducting means for permitting the gas so produced to operate on the surfaces of the liquids in each container, a solution mixing device and foam-discharge device and solution delivery lines leading from the respective containers to said solution mixing device and foam-discharge device, whereby said gas pressure is made effective to deliver the solutions and discharge the foam.
8. Fire extinguishing apparatus comprising containers in which mutually reactive foam-making solutions are normally kept separate, a mixing chamber, connections for placing the interior of each of said containers in communication with said mixing chamber, and pumps in said respective connections for forcing solutions from said containers to the mixing chamber, additional means of communication between said mixing chamber and both of said containers for conducting thereto gas generated by contact of the solutions in said chamber, and a solution delivery line from each of said containers to a mixing space in which foam is formed and from which it is discharged.
9. A fire extinguishing apparatus comprising solution containers for holding mutually reactive foam-forming solutions, solution lines connected to said containers, a mixing chamber communicating with the solution containers, means for pumping the solutions from the containers to the mixing chamber for forcible mixture of the solutions therein to produce a relatively high pressure foam, and means for conducting said foam back to the containers to exert a relatively high operating pressure on the solution surfaces therein to drive the solutions through the solution lines.
10. A fire extinguishing apparatus comprising solution containers for respectively holding mutually reactive foam-making solutions, solution delivery lines connected respectively to said containers, a mixing chamber, separate means connecting each of the containers with the mixing chamber, said means comprising a dry pipe system, a pump in each of the connecting means operative to drive the solutions from the containers to the mixing chamber into forcible

contact therein to produce a relatively high pressure foam, and means for conducting said foam back to the containers to exert a relatively high operating pressure on the solutions therein to drive the solutions through the solution lines.

11. A fire extinguishing apparatus comprising solution containers for respectively holding mutually reactive foam-making solutions, solution delivery lines connected respectively to said containers, a mixing chamber, separate means connecting each of the containers with the mixing chamber, a low pressure pump in each of the connecting means operative to drive the solutions from the containers to the mixing chamber for forcible mixture therein to produce a relatively high pressure foam, means for conducting said foam back to the containers to exert a relatively high operating pressure on the solutions therein to drive the solutions through the solution delivery lines, and means for simultaneously operating said pumps at a definite speed ratio.

12. A fire extinguishing apparatus comprising solution containers for respectively holding mutually reactive foam-making solutions, solution delivery lines connected to said containers, a mixing chamber, separate means connecting each of the containers with the mixing chamber, a pump in each of the connecting means operative to drive the solutions from the containers to the mixing chamber for forcible mixture therein to produce a relatively high pressure foam, means for conducting said foam back to the containers to exert a relatively high operating pressure on the solutions therein to drive the solutions through the solution delivery lines, and means for simultaneously operating said pumps, said last named means including a temperature controlled motor.

Signed at New York, in the county of New York and State of New York, this 3rd day of February A. D. 1921.

FRANK A. EPPS.
